UNITED STATES PATENT OFFICE.

CHARLES T. CUSTER, OF PASCO, WASHINGTON,
WATER-MOTOR.

1,191,950. Specification of Letters Patent. Patented July 25, 1916.

Application filed July 20, 1915. Serial No. 40,942.

TO ALL WHOM IT MAY CONCERN:

Be it known that I, CHARLES T. CUSTER, a citizen of the United States, residing at Pasco, in the county of Franklin, State of Washington, have invented certain new and useful Improvements in Water-Motors; and I do hereby declare the following to be a full, clear, and exact description of the invention, such as will enable others skilled in the art to which it appertains to make and use the same.

This invention relates to a water motor which is adapted to be operated by means of the current of a stream.

An object of the invention resides in the provision of a device which is simple in construction and which develops the maximum amount of power by its rotation caused by the current of a stream.

With this and other objects in view, such as will appear as my description progresses, my invention comprises the combination and arrangement of parts as set forth in and falling within the scope of the appended claims.

In the drawing: Figure 1 is an elevational view of my device; Fig. 2 is a vertical longitudinal sectional view; Fig. 3 is an end elevation; and Fig. 4 is a sectional view of the rotor.

Referring to the drawing by reference characters wherein like parts are indicated by like characters throughout the several views: In the embodiment of my invention shown in the drawing, I have illustrated a float 1, from one end of which depends a bearing member 2 and from the other end of which a tubular casing 3 depends. This casing extends above the upper surface of the float 1 and is supported by a brace 4. The lower end of this casing 3 is provided with a bearing member 5. Revolvably mounted in the bearing members 2 and 5 is a shaft 6 on which is secured a pulley 7 which pulley is located within the casing 3. The upper end of the casing 3 is provided with a bearing 8 in which a pulley 9 similar to the pulley 7 is mounted, being supported by a shaft 10. A belt 11 passes over these pulleys 7 and 9 and a relatively larger pulley 12 is secured to the shaft 10. Thus it will be seen that upon the rotation of the shaft 6, the pulley 12 will be set in motion and the power may be transmitted therefrom for any suitable purpose. In order that this shaft 6 may be set in motion by

the current of a stream, I have mounted a rotor thereon which consists of a top-shaped core having a frusto-conical portion and a hemispherical portion. This core is spaced from the bearing member 2 by means of a sleeve 13 which is held in place upon the shaft by a nut 14. A plate 15 is firmly attached to the hemispherical portion of the core and is secured to the shaft. Extending outwardly from this plate is a pair of arms 16 and 17 which are bent to extend in opposite acute angular relationship through the shaft 6 as clearly illustrated in Fig. 4 of the drawing. Secured to the arm 16 is a spiral blade 18 which is coiled about the core of the rotor and is secured between the end of the core and the end of the sleeve 13. A considerable space is left between the face of the core and the inner edge of the said blade 18. This space may be varied to accommodate the motor to the velocity of the stream in which it is installed. A second blade 19 is secured to the other arm 17 and extends about the core parallel to that of the blade 18 and is extended beyond the end of the said core. This extended end of the blade is secured between the end of the sleeve 13 and the nut 14. A space is left between the inner edge of this blade 19 and the core. The spaces between the blades 18 and 19 may be varied at will. The spaces between the blades and the core allow the water to pass therethrough so that it will not be backed up by the motor to cause an eddy. In the latter case the eddy would of course greatly interfere with the operation of the motor in as much as the full force of the current would not strike the blades.

From the foregoing description it will be seen that I have provided a water motor which is simple in construction and which may be readily installed.

While I have illustrated and described a particular embodiment of my invention it has merely been for the sake of convenience and I do not wish to be limited to that particular embodiment as it is obvious that numerous changes may be made in the details of construction without departing from the spirit of the invention or without exceeding the scope of the claims.

What I claim is:—

1. In a water motor, the combination with a rotary shaft, of a rotor mounted thereon, the said rotor including a core having a frusto-conical portion and a hemi-spherical

- portion, a pair of arms extending outwardly in opposite directions from the hemi-spherical portion and spiral blades secured to the arms and extending about the said core.
- 5 2. In a water motor, the combination with a shaft, of a rotor mounted thereon, the said rotor including a core having a pair of outwardly extending arms, a blade secured to one of said arms and passing about the core in a spiral path, a sleeve mounted on the shaft, the said blade being engaged with the shaft between the end of the sleeve and the adjacent end of the core, a second blade

secured to the other of said arms and extending about the core and sleeve in a spiral 15 path and engaged with the shaft at the other end of the sleeve and a nut adjustably mounted on the shaft to maintain the ends of the blades in place.

In testimony whereof, I affix my signature, in the presence of two witnesses.

CHARLES T. CUSTER.
